UNITED STATES PATENT OFFICE.

HARRY C. SCHWEMLEIN, OF CINCINNATI, OHIO, ASSIGNOR OF ONE-HALF TO DANIEL B. BRYAN AND ONE-HALF TO WILLIAM SCHWEMLEIN, OF CINCINNATI, OHIO; MARY B. BRYAN, OF FAYETTE COUNTY, KENTUCKY, ADMINISTRATRIX OF SAID DANIEL B. BRYAN, DECEASED.

FOLDING DOOR.

1,069,733.

Specification of Letters Patent. Patented Aug. 12, 1913.

Application filed September 23, 1910. Serial No. 583,519.

To all whom it may concern:

Be it known that I, HARRY C. SCHWEMLEIN, a citizen of the United States, residing at Cincinnati, in the county of Hamilton and State of Ohio, have invented new and useful Improvements in Folding Doors, of which the following is a specification.

This invention relates to a folding door of that type composed of a plurality of vertically-movable sections which are simultaneously raised to open the door and simultaneously lowered to close the same, the door being particularly adapted for use in factories, freight sheds, and the like, where the doors are often of considerable size and weight.

The invention has for one of its objects to improve and simplify the construction and operation of doors of this character so as to be comparatively simple and inexpensive to manufacture, reliable and efficient in use, and readily manipulated. The door is also designed to occupy little space, to be rigid and non-sagging, regardless of its size, and to be weather-tight when closed.

Another object of the invention is the provision of a novelly constructed door in which the sections thereof are counterbalanced by a single weight and can be raised by the turning of a crank or equivalent device so that the door sections will reach full open position at the same time.

A further object is the employment of novel connecting means between the movable sections of the door so that the raising and lowering mechanism may be connected with only the lowermost section to cause corresponding movement of the other section or sections at different speeds.

A further object is the provision of means whereby all the door sections can, after they have been raised to alining position, be thrown to a horizontal position to complete the opening movement of the door, the said swinging movement being effected by the same mechanism which raises the movable door sections to such alining position. In this form of my door, the lower door section or sections, upon being raised, are received by guides formed on the face of the upper door section which thereby constitutes a carrier for receiving the door sections and car-

rying the same into horizontal position. In connection with this form of my device, the form and means of operation of the carrier and for coördinating the same with the lower door sections, constitute features of my invention.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate certain embodiments of the invention, Figure 1 is a front view of a door constructed in accordance with one form of my invention with the sections thereof shown in closed position. Fig. 2 is a vertical section of the door with the sections or panels thereof in closed position. Fig. 3 is a similar view with the door sections in open position. Fig. 4 represents a vertical section similar to Fig. 2, of the modified form of door adapted to be swung into horizontal position; Fig. 5 is a vertical section similar to Fig. 4, in which the door sections have been moved into the carrier and the latter has been moved part way into horizontal position; Fig. 6 is a vertical section of the same construction, in which the carrier with the door sections contained therein, has been moved into fully horizontal position; and Fig. 7 is a horizontal section showing the mechanism for raising and lowering the door panels.

Similar reference characters are employed to designate corresponding parts throughout the views.

Referring to the drawings, and more particularly to Figs. 1, 2 and 3, the reference characters 1, 2 and 3 designate, respectively, the lower, intermediate and upper sections or panels of a door constructed in accordance with one form of my invention, which are capable of being raised to an alining position side by side in front of a transom 4 at the top of the doorway. The ends of the sections 1, 2 and 3 slide in vertical guideways 5, 6 and 7, respectively, on the jambs 8 of the door frame, the said guideways extending in the form of my device illustrated

in Figs. 1, 2 and 3 the width of top section of door above the top of the jambs. The guide-ways 5, 6 and 7, are side by side, and so placed that the left hand face of section 1 is in substantially the same vertical plane as the right hand face of section 2, referring to Fig. 2 of the drawings, and the left hand face of section 2 is in substantially the same plane as the right hand face 10 of section 3, so that the construction is very compact.

The door panels are adapted to be raised to open position and lowered to closed position by the turning of a crank 9 or equivalent device arranged at one side of the door frame. This crank is provided with a sprocket wheel 10 around which passes the lower end of a sprocket chain 11, the upper end of the said chain passing around a 20 sprocket wheel 12 fastened to a shaft 13 at the upper right hand corner of the door frame, Fig. 1. On this shaft 13 is a pinion 14 that meshes with a gear 15 on another shaft 16 arranged above the shaft 13. On 25 the shaft 16 is a sprocket wheel having two rows of teeth 17 and 18 that mesh respectively with sprocket chains 19 and 20, the chain 19 extending downwardly along the right side of the door frame to connect with the bottom panel 1 and the chain 20 extending horizontally across the top of the door frame to and around a guide pulley or sprocket 21 at the upper left corner of the transom and from here it extends downwardly along the 30 left side of the door frame to connect with the bottom panel of the door. The lower ends of the chains or flexible elements 19 and 20 are connected respectively with forwardly-extending brackets 22 and 23 at the 35 lower corners of the bottom panel, so that an even vertical pull will be exerted thereon when the crank 9 is turned to open the door. In order to counterbalance the weight of the door sections or panels, a single counterbalancing weight 24 is provided and it 40 is to this that the chains 19 and 20 are connected. This weight is adapted to run in a vertical casing or box 25 at the right side of the door frame.

50 The above described arrangement of lifting means for the door is merely illustrative.

The panels 2 and 3 are operatively related to the bottom panel 1 so that as the latter is lifted to open position, the other 55 sections will be lifted therewith and as the door descends to closed position, all of the sections will descend at the same time to their proper positions. The closing of the door in the form of my invention illustrated, 60 is by gravity under the restraint of the crank 9. The means which I consider best adapted for causing upward movement of the bottom door section to raise the other door sections and which constitutes a specific 65 part of my invention, will now be described.

The upper corners of the bottom panel are connected by chains or flexible elements 26 to the lower corners of the upper panel 3, whereas the upper corners of the intermediate panel 2 are connected, by chains or 70 flexible elements 27, with the lower corners of the transom, and in order to do this the chains 26 pass under the panel 2 while the chains 27 pass under the panel 3. On the panels 2 and 3 are guide pulleys 28 or equivalent anti-friction devices around which the chains 26 and 27 pass and whereby the sections 2 and 3 are supported. It is obvious that by means of this construction the panel 2 is lifted when the panel 1 rises and the panel 3 moves upwardly with the panel 2. Although the respective panels travel different distances from closed to open position, or vice versa, they all move together and reach the upper end of the 80 doorway at the same time, the panel 1 moving three times as fast as the panel 3 and the panel 2 moving twice as fast as the panel 3. It will be obvious that in this connection my invention is not limited to the 85 exact number of panels or door sections illustrated but is equally applicable to any number of sections, the flexible means 26, 27, etc. extending in each instance from the upper edge of a lower panel around the bottom of the next higher panel and being connected to the lower edge of the panel above that or to a fixed portion of the frame work as the transom 4, as the case may be. The 90 number of sections can be increased by merely increasing the number of guideways, and space occupied transverse to the planes of the sections will increase with the number of sections; substantially only by the thickness of the sections. This is, because, 100 by the construction shown, the sections can slide over each other without any waste space between the same, the guide pulleys being so arranged as to permit a direct or substantially direct vertical movement of 105 the flexible elements between each guide pulley and the next higher section whereby binding of the sections is obviated.

In the construction shown in Figs. 4 to 7, 115 inclusive, the door is made up of sections 1^a, 2^a and 3^a, the first two being movable in vertical guideways 5^a and 6^a. The section or panel 3^a is secured against vertical sliding movement in a frame or carrier 29, which carries guide ways, which, in the normal or 120 closed position of the carrier shown in Fig. 4, are in alinement with the guideways 5^a and 6^a, mounted on the door frame. This construction permits the lower and intermediate panels to be lifted from the guideways 125 5^a and 6^a into the alining guideways of the carrier so that the carrier with the door sections contained therein may then be moved from a vertical position into a horizontal 130 position, as shown in Fig. 6. The means for

lifting the panels and for causing upward movement of the lower section to raise the upper sections, is preferably the same as that described in connection with the first form 5 of my device. As illustrated, the intermediate section 2^a carries at its lower edge, a guide pulley similar to pulley 28, shown in Fig. 2, and a chain or flexible element similar to chain 26 passes, as illustrated, from 10 the upper edge of section 1^a around the guide pulley referred to and is secured at its upper end to the lower edge of section 3^a. Upon lifting the bottom section, the same traveling in its guideway 5^a and subsequently 15 in the alining guideway of carrier 29, moves across the face of section 2^a and the latter moves across the face of section 3^a in the same manner as described in connection with Fig. 2, sections 2^a and 1^a arriving 20 in alinement with each other and with section 3^a in the carrier 29 at the same time.

The mechanism for raising and lowering the lower and intermediate panels is employed to swing the panels to horizontal position, and this swinging movement occurs 25 at the final part of the opening movement of the door. At one side of the door frame is arranged the operating crank 30 which is connected by a sprocket chain 31 with a 30 sprocket wheel 32 on a shaft 33 adjacent the top of the door frame, the said shaft being connected by a gearing 34 with a shaft 36 on which are spaced sprocket wheels 37 and 38. Over these wheels pass suspension chains 39 35 and 40 that are connected with the lower corners of the panel 1^a, and these chains are connected with the counterbalance weight 41. By turning the crank 30 in the proper direction the lower and intermediate panels 40 are raised into the carriers 29 and further movement of the crank causes the carrier to swing as shown in Fig. 5 until a horizontal position is reached, as shown in Figs. 5 and 6.

45 The carrier is mounted in position so that normally the section 3^a closes the upper portion of the door opening with the carrier guideways in alinement with the guideways 5^a and 6^a on the door frame. The carrier is 50 supported by links 42 which are pivotally mounted at 43 on pins carried by bearings 44 secured to the wall above the door way. The links 42 are pivoted to carrier 29, as shown at 45. Preferably, as shown, the links 55 are pivoted to the wall at a point some distance above the door way and to the carrier at a point above the middle thereof, the construction being such that when the bottom and intermediate panels are fully raised in 60 the carrier, continued upward movement of the bottom panel will cause the links 42 to swing outwardly. The links 42 are pivoted to the carrier at some distance from the door opening so that the links 42 are inclined to 65 the vertical sufficiently to cause the carrier

and section 3^a carried thereby, to press tightly into position to close the door opening.

The lower corners of the carriers are provided with anti-friction means such as the rollers 46 illustrated which ride on vertical 70 tracks 47 provided on the door frame so that the carrier with the panels carried thereby can freely move to and from horizontal position.

In the normal or closed position of the 75 door, the top of section 1^a extends slightly above the lower edge of section 2^a and the upper edge of section 2^a extends slightly above the lower edge of section 3^a, the sections thus over-lapping to make a tight closure. The section 3^a, when in closed position, is not restrained or held against the doorway by any means except the pivoted links 42 and the upper end of section 2^a, which, as stated, may slightly overlap the 80 lower edge of section 3^a when in closed position, if desired. When the sections 2^a and 1^a are lifted into the carrier, they rise entirely 85 out of the frame guideways 5^a and 6^a, so that the carrier is then held in closing position only by the inclination of links 42, which, as stated, holds the rollers 46 on the rear of the lower edge of the carrier in contact with vertical track or surface 47. The upper edge of the rear face of section 3^a 90 normally contacts a similar vertical surface above the doorway. When the carrier has been swung into horizontal position, as shown in Fig. 6, it is entirely supported by 95 links 42, the lower edge of the carrier contacting the vertical face of the wall, as shown, and the outer end of the carrier being supported by the links. Because of this construction, which I prefer to use and which constitutes a portion of my invention, 100 it is unnecessary to employ any additional means for supporting the carrier in its raised position, the inclination of the links being such and their connection with the carrier being at such a point, toward the outer end 105 thereof, that the carrier will be rigidly supported.

The sliding door sections 1^a and 2^a, as stated, are lifted fully into the carrier 29 into alinement with the door section 3^a, after 115 which continued upward movement of section 1^a causes movement of the carrier as a whole. This is caused by the sections 1^a and 2^a striking abutments in the carrier which prevent further movement of the sliding sections relative to the carrier. The abutments referred to in the preferred form of my device, as illustrated, consist of a rigid member 120 closing the upper ends of the guideways carried by the carrier. This member is represented by the straight line shown at 29^a in Figs. 5 and 6, which member extends the full width of the carrier and forms a stop or abutment against which the upper ends 125 of the sliding door sections strike when the 130

same have reached the upper limit of their movement in the carrier. This member 29^a likewise performs the function of stiffening the carrier and preventing the same from sagging when in vertical or normal position. The carrier as thus formed constitutes a box-like structure, as shown. This is of importance since there is a tendency for doors of this character when of wide span, as in the case of large warehouse doors, to sag considerably.

It will be noted that with this type of door, one, two, three or more sliding sections, such as 2^a and 1^a may be employed, it only being necessary to provide a sufficient number of guideways, such as 5^a and 6^a to accommodate the same, and the space transverse to the planes of the door sections being substantially only that equal to the thickness of the sections. No guideway similar to 5^a or 6^a is required for the section 3^a and its carrier, but merely a vertical plane surface or surfaces, such as the track 47, parallel to the plane of section 3^a for the rollers 46 to travel upon. If the number of sliding sections and guideways, such as 5^a and 6^a are increased, the number of guideways carried by the carrier would, of course, be correspondingly increased. With this construction, the door is perfectly weather tight, since the sliding sections in normal or closed position, are all inclosed at the edges in the guideways 5^a and 6^a secured to the fixed structure of the doorway, and there is accordingly no open space between the outer edges of any section and the doorway structure.

It should be understood that while for purposes of illustration I have described the particular forms of my invention shown in the drawings, my invention is not limited strictly thereto but is as broad as indicated by the appended claims.

Having now described my invention what I claim as new and desire to protect by Letters Patent is:—

1. In a door structure, the combination with a door frame having vertical guideways at the lower portion of its opposite sides, of a normally vertical carrier normally covering the upper portion of the door opening and having guideways normally alining with said frame guideways, and provided with a stop, suspension means pivotally connected to said carrier and to a fixed point above said doorway, an upper door section carried by said carrier, a lower door section normally slidably mounted in said frame guideways, rollers mounted on the lower edge of said carrier and contacting a vertical surface of said door frame, and means for lifting said lower door section into the guideways of said carrier and into contact with said stop and thereafter causing said carrier to swing about said rollers

into horizontal position, substantially as described.

2. In a door structure, the combination with a door frame having vertical guideways at the lower portion of its opposite sides and a vertical track at its upper portion, of an upper door section normally covering the upper portion of the door opening, and carrying guideways normally alining with said frame guideways, rollers secured to the lower edge of said door section contacting said track, links pivotally connected to said door section and at their upper ends to a part secured to the said frame, said links normally extending diagonally upward toward the plane of said track, a lower door section normally slidably mounted in said frame guideways and movable therefrom into said upper section guideways, and vertically-acting means for lifting said lower section into said upper section guideways and thereafter swinging said two sections together about said rollers into horizontal position, substantially as described.

3. In a door structure, the combination with a door frame having a vertical track of a carrier normally covering the upper portion of the door opening and provided with an upper door section and guideways parallel thereto, and closed at the top, link suspension means pivoted to said carrier and to the frame above the door opening, and so inclined as to normally hold said carrier against said track, a lower door section normally covering the lower portion of the door opening and slidably mounted in line with said guideways, and lifting means for raising said lower section into said guideways and into contact with the closed ends thereof and thereafter raising said carrier and swinging the same about its lower edge contacting said track, substantially as described.

4. In a door structure, the combination with a door frame having a vertical track of a carrier normally vertically mounted opposite the upper portion of the door opening and provided with vertical guideways, having abutments, link suspension means pivoted to said carrier above the middle thereof and to the frame above the door opening and so inclined as to normally hold said carrier against said track, a sliding door section normally covering the lower portion of the door opening and slidably mounted in line with said guideways, and lifting means for raising said section into said guideways and into contact with said abutments and thereafter raising said carrier and swinging the same about its lower edge contacting said track, into a horizontal position in which the outer end of said carrier is supported entirely by said link means, substantially as described.

5. In a door structure, the combination with a door frame of a carrier normally ver-

- tically mounted opposite the upper portion of the door opening and provided with an upper door section adapted to cover the upper portion of said opening and a plurality 5 of vertical guideways at different distances from said door section, link suspension means pivoted to said carrier and to said frame and so inclined as to normally hold said door section against said frame, pivot 10 means carried by said carrier, and contacting said frame, vertical guideways mounted on said frame below and in line with said carrier guideways, sliding door sections connected together and mounted in said last 15 named guideways, and a single means for raising said sections into said carrier guideways and thereafter swinging said carrier about said pivot means under the restraint of said suspension means, substantially as 20 described.
6. In a door structure, the combination with a door frame having a vertical track, of a carrier provided with a door section parallel to said track, and parallel guideways adapted to receive sliding door sections, rolling means secured to an edge of 25 said carrier adapted to contact said track, and link suspension means pivotally connected to said carrier and said frame in such 30 a manner as to support said carrier and cause said rolling means to press against said track in any position of the same upon said track, substantially as described.
7. In a door structure, the combination with a door frame having a vertical track, of a carrier provided with a door section parallel to said track, and parallel guideways adapted to receive sliding door sections, said guideways being open at the bottom 35 and said carrier being provided at the top with a stiffening member closing the top of said guideways, pivotal means secured to the lower edge of said carrier adapted to contact said track, and link sus- 40 pension means pivotally connected to said carrier and said frame in such a manner as to support said carrier and cause said rolling means to press against said track in any position of the same upon said track, sub- 45 stantially as described.
8. In a door structure, the combination with a door frame of an upper door section, provided with a pair of guideways, link means for pivotally suspending the 50 same from said frame, said frame being provided with vertical guideways below and in line with said upper guideways when said upper section is in normal position covering the door opening, sliding lower and intermediate door sections in said frame guideways, a roller on the bottom of said intermediate section, a flexible connection passing around said roller and secured to the top of 55 said lower section and to the bottom of said upper section, respectively, means for lift- 60
- ing said lower section and said intermediate section therewith into said upper section guideways, and thereafter raising and swinging said upper section with sliding sections carried thereby out of the vertical, 70 under the restraint of said suspension means, substantially as described.
9. The combination of a door frame or similar structure having at opposite sides a plurality of vertical guideways, a normally vertical carrier at the upper portion of the structure having guideways normally alining with the first-mentioned guideways, links pivotally connected to the structure at a point above the carrier and also pivotally 75 connected with the latter, at a point above its center, said links normally being inclined at an angle to the plane of said guideways, panels movable from the guideways of the structure to the guideways of the 80 carrier and vice versa, counterbalancing means connected with the panels, and a single mechanism for first moving the panels into the carrier and thereafter moving the carrier upwardly from a vertical to 85 an approximately horizontal position.
10. In a door structure, the combination with a door frame of a carrier normally vertically mounted opposite the upper portion of the door opening, and comprising 90 an upper door section and a plurality of vertical guideways parallel thereto, having abutments, link suspension means pivotally 95 connected to said carrier and said frame, pivot means carried by said carrier and contacting said frame below and in line with said carrier guideways, sliding door sections mounted in said last named guideways, flexible connections one less than the number of said sliding sections, secured respectively to the tops 100 of each of said sections except the uppermost, each connection passing thence around the lower end of the next higher section and secured at its upper end to the sliding section or carrier immediately above that, and means for lifting the bottom section and thereby raising all of said sliding sections 105 into said carrier guideways into contact with said abutments, and thereafter swinging said carrier about said pivot means under 110 the restraint of said suspension means, substantially as described.
11. In a door structure, the combination with a door frame having at opposite sides a plurality of vertical guideways, a normally vertical carrier mounted opposite the upper portion of the door opening having guideways normally alining with the first- 115 named guideways, suspension means pivotally connected to said carrier and said frame, sliding door sections normally mounted in extended relation in said frame guideways and movable therefrom into said carrier guideways, flexible connections secured 120 respectively to the tops of each of said sec- 125
- 65 upper section, respectively, means for lift- 130

tions except the uppermost, each connection extending thence around the lower end of the next higher section and secured at its upper end to the section or carrier immediately above that, and means for lifting the bottom section and thereby raising all of said sliding sections into said carrier and thereafter swinging said carrier upwardly

from a vertical to an approximately horizontal position, substantially as described. 10

In testimony whereof I affix my signature in presence of two witnesses.

HARRY C. SCHWEMLEIN.
